DETENTION WINDOW AND METHOD OF
GLAZING SAME

William D. Bayley, Springfield, Ohio

Application December 14, 1936, Serial No. 115,752

8 Claims. (Cl. 189—64)

This invention relates to windows and the method of glazing same.

This invention is related to the disclosures in my Patents No. 2,020,046 and No. 2,042,876 and the disclosures in my copending applications Serial No. 58,915 and No. 48,176 ripening into Patents No. 2,064,334 and No. 2,064,335 respectively, issuing on December 15, 1936.

An object of the present invention is to provide a method of glazing a detention window wherein the glazing is seated in fixed channels.

Another object of this invention relates to the method of constructing and arranging the masonry surrounding the window.

Another object of this invention is to provide a sill-less window, wherein the glazing along the bottom of the window is seated directly in the masonry construction or whatever construction makes the horizontal of the opening in the absence of metal.

Another object of this invention is to provide a window that is cheap, efficient, easily constructed; but at the same time dependable.

Another object of this invention is to provide a composite bar having a portion thereof of toolable material joined to another portion of tool resistant material.

Another object of this invention is to reinforce the frame structure extending across the window in spaced relation from the bottom of the window opening.

Other objects and advantages reside in the construction of parts, the combination thereof and the mode of operation, as will become more apparent from the following description.

Fig. 1 is a front view of a window.

Fig. 2 is a transverse section of the glazed window taken substantially on the line 2—2 of Fig. 1.

Fig. 3 is a vertical sectional view of the glazed window taken substantially on the line 3—3 of Fig. 1.

Fig. 4 is another vertical sectional view of the glazed window taken substantially on the line 4—4 of Fig. 1.

Fig. 5 is an enlarged detail fragmentary view of portions of the channel in the wall bounding the window, as seen before glazing.

Fig. 6 is a sectional view of another modification showing the wall channel before glazing.

Fig. 7 is another fragmentary sectional view showing another modification during construction.

Fig. 8 is another fragmentary sectional view

showing another modification during construction of a wall bounding the window.

Fig. 9 is another fragmentary sectional view of the modification disclosed in Fig. 7, showing a step in construction.

Fig. 10 discloses a cross sectional view of an unglazed window to illustrate another modification having a cast iron pipe embedded in the masonry to reinforce the sill extending across the bottom of the window.

Fig. 11 is another cross sectional view of the modification disclosed in Fig. 10, looking in the opposite direction.

Fig. 12 is a detail fragmentary sectional view taken substantially on the line 12—12 of Fig. 10.

Fig. 13 is a fragmentary detail view showing the insertion of the metallic channel shown in Fig. 6.

Fig. 14 discloses another modification before glazing.

In penal institutions and the like it is very desirable to have the glazing seated in channels on all sides, so that the inmate cannot very well without discovery peel away the putty and remove the glass.

Furthermore, it is desirable to mount the detention bars in spaced relation from the masonry along the bottom of the window to prevent corrosion. Use has demonstrated, particularly in packing houses and wherever subjected to steam

and to chemical fumes, the life quality of the bottom horizontal portion of a steel window is shorter than the life quality of other portions of the window. The reason for this is that such portions are partially embedded or inaccessible

for repainting and therefore retain moisture and dampness. Detention windows are also liable to have a similar weakness due to the type of steel used in detention bars. Erosion of the detention bars, resulting in failure, may be disastrous, creating public danger.

This has been overcome in the present embodiment by arranging a frame structure that terminates in spaced relation from the masonry extending along the bottom of the window. By so doing, no metal comes in contact with the masonry. The space between the masonry along the bottom of the window and the lowest portion of the metallic frame structure is closed by glazing, having the upper edge seated against the lowest portion of the metallic frame and the lower edge secured directly to the masonry extending across the bottom of the window by putty or other suitable plastic material.

In the present invention an arrangement of

channels has been made wherein it is possible to seat the glazing in channels on all sides without having a side of the channel removable. This has been accomplished by providing oppositely disposed end channels, at least one of which is sufficiently deep to pass the window pane into the channel and slip the opposite edge of the window pane into the other end channel. In order to do this it has been found necessary to make the channel along one side of the window pane sufficiently wide so as to provide clearance beyond the face of the muntin bar for the window pane. In other words, the channel in the wall has been made sufficiently wide so as to extend beyond the inner face of the muntin bar a distance sufficiently great to accommodate the thickness of the glazing.

Referring to the drawings, the reference character 20 indicates a plurality of vertically disposed detention bars having the upper ends seated in the masonry 22 bounding the ventilating area. The detention bars are held in fixed spaced relation by a plurality of transversely disposed duo-functional rail and muntin bars 24. The ends 25 of the muntin bars 24 preferably extend into the masonry bounding the window opening.

The lower ends of the detention bars 20 are arranged in spaced relation from the masonry 26 extending across the bottom of the window. The 30 masonry along the bottom may include a horizontal portion 28, a shoulder 30 and a sloping portion 32. It has been found that the detention bars that are embedded in the masonry extending across the bottom of the window rust and deteriorate very rapidly. In order to eliminate this rusting and deteriorating of the detention bars, the lower ends of the detention bars have been arranged in spaced relation from the masonry extending across the bottom of the window.

In order to provide a satisfactory support for the lower portion of the detention bars, the lower duo-functional rail and muntin bar designated by the reference numeral 34 has been spaced only 45 a short distance from the masonry extending across the bottom of the window. It may be only an inch, two inches, or possibly four or five inches from the bottom. The duo-functional rail and muntin bar 34 may be of heavier material than the other rail bars, so as to prevent the inmates from bending or distorting this duo-functional rail and muntin bar. In some respects, the duo-functional rail and muntin bar may be referred to as a sill supporting the lower end of the detention bar 20.

The duo-functional rail and muntin bars 24 and 34, respectively, are preferably provided with a horizontal portion 36 terminating in a downwardly projecting flange 38 extending along the 60 outside of the detention bars 20. The opposite end of the downwardly sloping portion 36 supports and is integral with an H-shaped portion 40. The upper channel 42 being smaller or shallower than the lower channel 44, these channels receive the glazing as will appear more fully later.

As the duo-functional muntin and rail bars 24 and 34 respectively, have their outer ends seated in the masonry bounding the window, the outside frame of the conventional windows has been eliminated. In this respect, this is similar to my 70 Patent No. 2,020,046.

The channels along the sides of the window may be formed by attaching a suitable form member 54 to the rail bars and muntin bars 24 and 34. In the modification disclosed in Fig. 7 a ver-

tical spacer bar 56 has been fixedly and permanently attached to the duo-functional rail and muntin bars 24 and 34 respectively. Member 56 is preferably attached by welding. The form member 54 seated against the vertical bar member 56 is held in position by suitable wires 60 wrapped around members 54 and 56. Members 54 terminate at the edges of the H-shaped members 40, as best seen in Fig. 9. The channel formed by removing form member 54 is used as a glazing seat and furthermore, the channel to the right, as seen in Fig. 2, is sufficiently wide to permit the insertion of the window pane without providing a removable side for the channel. The channel to the left of Fig. 2 may be formed by 15 a rigid form member 55 shown in Fig. 11. Member 55 and its resulting channel 52 need not be wider than the channels 42 and 44 found in members 24 and 34.

The glazing 70, as may best be seen by referring to the dot and dash position shown in Fig. 3, is positioned in offset relation, extending into the channel 50 so as to clear the wall containing channel 52. The glazing when in this position is in readiness for rotation in the bottom channel 25 in the direction of the arrow 72 into the full line position. After it has been rotated so as to have the lower edge of the window pane seated in the channel 42, the window pane is moved from the dot and dash position shown in Fig. 2 to the 30 full line position, so as to have the edge shown to the right of Fig. 2 seated in the channel 52 which is narrower than the channel 50 shown to the left of Fig. 2. It is necessary to have only one of the channels sufficiently wide to extend beyond the fact of the duo-functional muntin and rail bars 24 and 34 respectively.

In the modification disclosed in Fig. 8, members 54 and 56 have been omitted; but instead of these a form member 74 has been used, which is considerably wider than the depth of the channel 50. This permits the use of a wire 76 passed through the opening 78 in the horizontal portion 36 of members 24 or 34, as the case may be. The form member 74 is provided with suitable holes for the passage of the wire 76. In order to properly straddle the H-shaped portions of the muntin bars 24 and 34, member 74 has been provided with suitable notches. Members 78 have been placed in the channels 42 and 44 to prevent concrete from filling the ends of the channels. After the concrete has been poured the wires 76 are cut and member 74 removed from the face of the wall bounding the window opening, so as to vacate the channel 50.

For some types of structures it is desirable to face the channels 50 and 52 with a suitable metallic member. Then removably mounted form members such as 54 or 74 may be omitted, the metallic channel members performing the same function. In Fig. 5 a U-shaped member 80 has been used. It passes through suitable apertures provided therefor in the muntin and rail bars 24 and 34. This member is provided with a pair of reentrant flanges 82 seated in the edge of the concrete. Tongues 84 may be struck out from the U-shaped member 80 to further support it in the masonry.

In the modification disclosed in Figs. 6 and 13, tongues 86 have been struck out from the legs of 70 the U-shaped member 88 at spaced intervals and embedded in the concrete. By referring to Fig. 13 it may be seen that the tongues 86 are also used to hold member 88 in fixed spaced relation with respect to the bars 24. The tongues 75

may be arranged in staggered relation to adequately hold member 88 in position without excessively weakening the same.

Referring to the modification disclosed in Fig. 14, a pair of metallic members 90 and 92 cooperate to form the channel 50 without either member being passed through the muntin and rail bar. Instead, the L-shaped member 90 has one flange 94 welded to the faces of the rail and muntin bars 24 and 34. Member 90 is preferably made from comparatively heavy material, thereby giving rigidity to the window assembly to facilitate handling at the factory, in shipment and during erection of the structure. Furthermore, no filler members are needed while pouring the concrete. Member 90 preferably extends continuously throughout the entire height of the window opening. Member 92, on the other hand, is preferably of a suitable length to fit between adjacent muntin bars, so as to span the approximate width of each window pane.

Whenever the windows are comparatively wide, it may be desirable to reinforce or support the sill muntin and rail bar 34 at spaced intervals. In the modification shown in Figs. 10 to 12 this has been accomplished by a cast iron pipe 100 having its lower end embedded in the masonry 26 and the upper end encircling the lower end of a detention bar 20. The pipe 100 fits snugly into the space between the downwardly projecting flange 38 and the end of the detention bar 20 and into the space between the H-shaped portion 40 and the bar 20. The flange 38 and the H-shaped portion prevents rain from driving in over the top of the pipe 100 and the horizontal portion 36 of the muntin and rail bar 34. One or more pipes 100 may be used along the sill of each window. Although cast iron is far more rust resistant than the material used in the muntin bars 34 and the detention bars 20, other more non-corrosive material may be used in these pipes, such as brass, copper, "Duralumin", tile, or other metallic or vitreous material.

The pipe 100 preferably has a web 102 welded or otherwise attached thereto, adapted to project between adjacent window panes. In addition to forming seats for the glazing, the web 102 reinforces the pipe so as to give the assembly more rigidity.

Instead of a round or tubular member 100 having the web 102 and the shoulders 104, any other suitable reinforcing member may be used. This member may be provided with anchoring means in the masonry. For other types of structures the reinforcement may be accomplished by an upwardly extending concrete projection, or the like, to provide a rail support.

Although the preferred modification of the device has been described, it will be understood that within the purview of this invention various changes may be made in the form, details, proportion and arrangement of parts which generally stated consist in a device capable of carrying out the objects set forth, in the novel parts, combination of parts and mode of operation, as disclosed and defined in the appended claims.

Having thus described my invention, I claim:

1. A metallic window assembly for use in a window opening in a wall of masonry, said assembly including a metallic frame having a plurality of horizontally disposed muntin bars, and a sheet metal channel member mounted in the wall on one side of the window opening, said channel member passing through apertures near the end of the muntin bars, and including tongues

deflected from the walls of the channel adapted to fasten the channel in the masonry bounding the window opening.

2. A window assembly for use in a window opening in a wall of masonry, said assembly including a detention rail guard having a plurality of vertically disposed detention bars held in fixed spaced relation by a plurality of horizontally disposed duo-functional rail and muntin bars, each of said duo-functional rail and muntin bars being provided with a pair of oppositely disposed glazing channels, the walls bounding the sides of the window opening being provided with glazing channels aligned with the glazing channels in the muntin bars, the glazing channel in the wall on one side having a width substantially equal to the glazing channel in the muntin bars, the glazing channel in the opposite wall being wider so as to extend beyond the face of the muntin bars, and window panes mounted in the glazing channels, said wider channel being utilized to facilitate glazing.

3. A metallic window assembly for use in a window opening in a wall of masonry, said assembly including a plurality of parallel muntin bars having the ends thereof embedded in the masonry bounding the window opening, and channel means embedded in the masonry, said channel means including an angle bar having one leg welded to the muntin bars and the other leg extending parallel to the longitudinal axis of the muntin bars but in spaced relation from the face of same, and a second angle bar having one leg overlapping the first mentioned leg, the other leg of the second angle bar extending parallel to the longitudinal axis of the muntin bars to form a glass supporting seat.

4. A metallic window assembly for use in a window opening in a wall of masonry, said assembly including a plurality of parallel muntin bars having the ends thereof embedded in the masonry bounding the window opening, and channel means embedded in the masonry to form a glazing seat, said channel means including an angle bar having one leg abutting the faces of the muntin bars and welded thereto, said angle bar giving the window assembly rigidity during assembly, and a second angle bar disposed between adjacent muntin bars, one leg of each angle bar cooperating to form the bottom of said glazing channel, the other leg of each angle bar constituting the walls of the channel.

5. A metallic window assembly for use in a window opening in a wall of masonry, said assembly including a plurality of parallel muntin bars having the ends thereof embedded in the masonry bounding the window opening, and channel means embedded in the masonry to form a glazing seat, said channel means including one continuous angle bar welded to the muntin bars, and a plurality of aligned bars, each secured to the continuous angle bar, each space between adjacent muntin bars being spanned by one of said plurality of angle bars so as to form glazing seats.

6. A metallic window assembly for use in an opening in a wall of masonry, said assembly including a metallic frame having glazing seats aligned with glazing channels in the sides of the masonry bounding the opening in the wall, said frame having at least one horizontally disposed muntin bar extending across the bottom of the frame arranged in spaced relation from the masonry extending across the bottom of the window, glazing mounted in the window frame and a closure for the space between the bottom of the

- frame and the masonry extending across the bottom of the window opening, said closure having its lowest edge supported upon the masonry and the upper portion in contact with said frame.
5. 7. A detention window assembly for a window opening in a wall of masonry, said assembly including a rail guard having a plurality of horizontally disposed duo-functional muntin and rail bars having the opposite ends embedded in the masonry bounding the window opening, said duo-functional muntin and rail bars having longitudinal glazing channels, one opening upwardly and

the other opening downwardly, a plurality of vertically disposed detention bars intersecting the muntin bars, and vertical channels in the masonry bounding the sides of the window, said vertical channels being aligned with the channels in the duo-functional muntin and rail bars and cooperating therewith in forming glazing seats.

8. A device as set forth in claim 7 having the glazing channels in the wall provided with a metallic lining.

10

WILLIAM D. BAYLEY.
